D12-18. OR D 20,214 EX

DESIGN.

—o—
H. C. ARMSTRONG.
WAGON BODY.

No. 20,214.

Patented Oct. 21, 1890.

UNITED STATES PATENT OFFICE.

HENRY C. ARMSTRONG, OF PROVIDENCE, RHODE ISLAND.

DESIGN FOR A WAGON-BODY.

SPECIFICATION forming part of Design No. 20,214, dated October 21, 1890.

Application filed September 22, 1890. Serial No. 365,830. Term of patent 14 years.

To all whom it may concern:

Be it known that I, HENRY C. ARMSTRONG, a citizen of the United States, residing at Providence, in the county of Providence and State of Rhode Island, have invented and produced a new and original Design for Wagon-Bodies, of which the following is a full, clear, and exact description, reference being had to the accompanying photographic view, forming part of this specification.

This invention has reference to the peculiar and novel design of the main wagon-body independent of the cab or seat for the driver.

The drawing is a photographic view showing the wagon in perspective.

The leading feature of my design consists in the outline and configuration of a fort surmounted with a battlement and forming the main body of the wagon.

A is the main body of the wagon to which the present invention relates. It consists of a box or body of oblong horizontal section having rounded ends, the cross-section being of practically rectangular form.

B is the driver's seat. (Shown covered by

the cab C.) The arched bridge D forms a connection between the seat B and the main body A. The main body A is painted to represent a walled fort having a series of ports E and surmounted by a battlement consisting of a series of merlons F, separated by openings or embrasures.

The photograph shows the gun G surmounted on the fort and the flag H supported on a flag-staff over the fort.

Having thus described my newly-invented design, I claim as new and desire to secure by Letters Patent—

The design for a wagon-body herein shown and described, the same comprising the main body having the outline and configuration of a walled fort, and the connection between the seat and the main body having the outline and configuration of an arched bridge, as described.

HENRY C. ARMSTRONG.
